CAR CONSTRUCTION

John B. D. Thompson, Berwick, Pa., assignor to
American Car and Foundry Company, New
York, N. Y., a corporation of New Jersey

Application September 30, 1936, Serial No. 103,249

14 Claims. (Cl. 108—5.1)

This invention relates to car construction in general and in particular to passenger car construction.

In previous passenger car construction the underframe was relied upon as the sole strength member with the superstructure formed by a lot of connected parts forming a shell inclosing the passenger space. This shell was designed to resist lateral thrusts but was not relied upon as a strength member of the car. It is an object, therefore, of this invention to simplify the car construction by eliminating a plurality of the unnecessary roof parts and substitute a single structurally strong member.

Another object of the invention is to provide a combined deck plate, clerestory side, and carline support.

A further object of the invention is to provide a strong roof side member which will permit the elimination of unsightly eaves and water tables.

A still further object of the invention is the provision of an improved roof member of great strength which will effectively carry the stresses between the car end posts.

These and other objects of the invention will be apparent to those skilled in the art from a study of the following description and accompanying drawing, in which:

Figure 1 is a cross section through the upper portion of a passenger car constructed with the improved roof member;

Fig. 2 is a cross section of a car roof using the improved roof member of Fig. 1, and

Fig. 3 is a cross section similar to Fig. 1 but showing a modification thereof.

Referring now to the drawing in detail, it is seen that the car is of the monitor roof type having side plates 2 to which are fastened lower carlines 4, carrying the center roof carlines 6. The lower carlines of general U section have a curved portion 8 supporting the lower deck sheets 10 and a vertically extending portion 12 to which is attached the improved roof member A and the clerestory lining B.

The improved roof member shown in Figs. 1 and 2 consists of a lower outwardly directed flange 14 lapping and supporting the lower deck roof sheets, a vertically extending web 16 forming the clerestory sides, and an inwardly directed portion 18 conforming to the roof slope which portion is bent downwardly as at 20 and then flanged inwardly as at 22 to form a support for the center roof carlines. Forming the member in this shape eliminates a major portion of the joints heretofore used and gives an extremely

strong beam having a lower flange or chord and a very strong top chord which takes the place of the upper deck plate. This top chord or upper deck plate is exceedingly strong since it caps the upper ends of the lower carlines and being rigidly secured thereto the sides cannot spread and it becomes substantially a channel member. It is to be understood that these improved roof members extend from end post to end post as is usual and thus form parallel beams which will aid materially in the carrying of the car loads permitting a decrease in underframe strength.

The center roof carlines 6 are of general Z section having one flange 23 resting upon and secured to the roof member flange 22 by means 24 while the web of the carline is bent to form a flange 26 by means of which it is secured to the roof member and lower carlines through rivets 28 which firmly bind the three elements together. The upper flange 30 of the carline provides a 20 supporting and attaching means for the center roof sheet 32, the side edges of which are secured to the portion 18 of the roof member by means of rivets 34.

The supporting flange 22 not only supports the center roof carlines but provides an ideal support for the attachment of the ceiling panels 36 and the upper edges of the clerestory side finish 38 together with the molding securing strip 40. The molding 42 is held in place by this strip and it is only necessary to provide supporting means 44 at spaced points such as at the lower carlines. The lower edges of the clerestory side finish are secured to the upper flange 46 of the inner deck sill which is of angle formation and firmly secured to the lower carlines. The outwardly directed flange 48 of this deck sill provides a support for one edge of the lower deck finish 50 as well as the corner binding 52.

In order that the car may be ventilated or air conditioned, if desired, openings 54 are cut in the web 16 to which a ventilator or other means 56 may be secured by means 57 surrounding the opening. Z or other section members 58 are secured to the web adjacent the openings and provide a closed frame or box permitting passage of air to and from the interior of the car. These members have their flanges 60 directed toward each other and support the ventilator grating 62.

The modification shown in Fig. 3 is somewhat similar to that just described and wherever possible the same reference characters have been used. In this instance the center carline 6 has the lower flange 64 secured to the top of the lower carline, while the web flange 66 is secured

to the side member by means of rivets 68. The side member is of angle form having one long flange or leg 70 forming the clerestory side lapped and secured to an upwardly directed flange 72 of the lower deck sheet 10, while the short flange 74 is directed inwardly for attachment to the upper flange 76 of the center roof carline and to the center roof sheet.

To further tie the lower and upper carlines together the strip 78 is provided having one leg 80 attached to the lower flange of the center carline, while the other leg 82 is attached to the up-standing portion of the lower carline. These legs of the strip provide attaching means for the ceiling and clerestory finish 36 and 38 respectively, while the web portion 84 which joins the legs forms an admirable means to which the corner molding 86 may be secured.

In this latter construction it is seen that an extremely simple structure is used in which a number of unnecessary joints are eliminated without any sacrifice of car strength.

While the structures shown have been described more or less in detail, it will be obvious to persons skilled in the art that various changes may be made in the structures but all such changes are contemplated as fall within the scope of the following claims.

What is claimed is:

- 30 1. A monitor type car having upper and lower carlines, plate means attached to said lower carlines and forming a clerestory, said plate means also forming a part of the exposed portion of the car roof and a support for the upper carline.
- 35 2. A monitor type car formed in part by upper and lower carlines, externally arranged plate means secured to said lower carlines to form a clerestory, said plate means enveloping a portion of the lower carlines and having an inner extended portion forming a support for said upper carlines, said support also serving as a support for a clerestory lining.
- 40 3. A monitor type car formed in part by upper and lower carlines, externally arranged plate means secured to said lower carlines to form a clerestory, said plate means enveloping a portion of the lower carlines and having an inner extended portion forming a supporting element for said upper carlines, said supporting element also serving as a support for a clerestory lining as well as for ceiling lining and molding.
- 45 4. An improved roof member for monitor type cars having upper and lower decks joined by a clerestory and comprising, a plate formed with a vertically extending clerestory portion, an outwardly directed lower deck portion, and an inwardly directed upper portion having a part thereof formed to underlie and support roof car-lines.
- 50 5. An improved roof member for monitor type cars having upper and lower decks joined by a clerestory and comprising, a plate formed with a vertically extending clerestory portion, an outwardly directed lower deck portion, an inwardly directed upper deck portion and a downwardly directed portion spaced from but substantially parallel to said clerestory portion.
- 55 6. An improved roof member for monitor type cars having upper and lower decks joined by a clerestory and comprising, a plate formed with a vertically extending clerestory portion, an outwardly directed lower deck portion, an inwardly directed upper deck portion, a down-

wardly directed portion spaced from but substantially parallel to said clerestory portion and a laterally directed upper carline supporting portion.

7. An improved roof member for monitor type cars having upper and lower decks joined by a clerestory and comprising a plate formed with a substantially channel section upper portion, the outer side of which is extended to form the clerestory. 5

8. An improved roof member for monitor type cars having upper and lower decks joined by a clerestory and comprising a plate formed with a substantially channel-shaped upper portion, one side of which is extended to form the clerestory and having its lower edge directed outwardly to constitute an attaching and supporting portion for the lower deck. 10

9. An improved roof member for monitor type cars having upper and lower decks joined by a clerestory and comprising a plate formed with a substantially channel-shaped upper portion, one side of which is extended to form the clerestory and having its edge portions directed outwardly and inwardly respectively to constitute attaching and supporting means for roof elements. 15

10. In a monitor type car, upper carlines, lower carlines having portions thereof directed upwardly, and plate means forming a clerestory, said plate means comprising a unitary member 30 secured to the lower carlines and lapping the upwardly directed portions thereof, the upper portion of said plate means being inwardly flanged to constitute a supporting and attaching element for the upper carlines. 35

11. In a monitor deck type car, upper carlines, lower carlines having upwardly directed portions, and plate means forming a clerestory, said plate means comprising a unitary member secured to the lower carlines and having its upper end portion formed to cap the upwardly directed portions of the lower carlines, and said upper end portion of said plate means being formed to provide a support for the carlines. 40

12. In a monitor type car, upper carlines, lower carlines having portions thereof directed upwardly, and a unitary member forming a clerestory, said unitary member comprising plate means having a flanged lower edge portion, the upper portion of said plate means being formed 50 to channel shape into which the upper end portions of the lower carlines extend, the free edge portion of said channel-shaped portion of said plate means being flanged in a direction opposite to that of the flange of the lower edge portion of said plate means whereby to provide a supporting and attaching element for the upper carlines. 55

13. A clerestory member for car roofs comprising a unitary plate means having a flanged lower edge portion, the upper portion of said plate being channel shaped and having its free edge portion flanged in a direction opposite that of the first named flange. 60

14. In a monitor type car, upper carlines, lower carlines having portions thereof directed upwardly, and plate means forming a clerestory, said plate means comprising a unitary structure secured to the lower carlines and lapping the upwardly directed portions thereof, the upper portion of said plate means being inwardly flanged to underlie and support the upper carlines. 65
